Primary Examiner—Stella Reid*Assistant Examiner*—Elizabeth J. Oswecki(74) *Attorney, Agent, or Firm*—Baker Donelson(57) **CLAIM**

The ornamental design for a necktie, as shown and described.

DESCRIPTION

FIG. 1 is a perspective view of the necktie showing my new design.

FIG. 2 is a front view thereof, the rear view being a mirror image thereof.

FIG. 3 is a right side view thereof, the left side view being a mirror image thereof.

FIG. 4 is a top view thereof; and,

FIG. 5 is bottom view thereof.

The broken lines in the views shows environmental features which are for illustrative purposes only and form no part of the claimed design.
